APPARATUS FOR OPERATING ON WIRE STOCK

Frederick W. Gaines, 3rd, Cleveland Heights, and William A. Ehler, South Euclid, Ohio, assignors to The Ajax Manufacturing Company, Euclid, Ohio, a corporation of Ohio

Application August 25, 1941, Serial No. 408,142

11 Claims. (Cl. 140—140)

This invention relates to improved apparatus for straightening wire stock and for cutting desired lengths from the leading end of the stock.

An object of our invention is to provide an improved arrangement in which the drawing, straightening, and cutting of the wire stock can all be carried out in the same machine and in a desired sequence during the forward travel of the stock.

A further object of our invention is to provide apparatus of this kind embodying novel stock feeding means as well as a novel cut-off mechanism by which desired lengths or sections of stock can be cut rapidly from the leading end and with greater accuracy than has heretofore been obtainable.

Yet another object of our invention is to provide apparatus of this kind having novel means for permitting fine adjustment of the stock gauge to be made while the machine is in operation.

The invention may be further briefly summarized as consisting in certain novel steps of procedure and in certain novel combinations and arrangements of parts, all of which are herein-after described in detail and particularly set out in the appended claims.

In the accompanying sheets of drawings:

Fig. 1 is a side elevation showing one embodiment of our improved apparatus for operating on wire stock;

Fig. 2 is a side elevation showing, on a larger scale, an intermediate section or unit of the machine which embraces the stock feeding and straightening means;

Fig. 3 is a plan view of such intermediate section or unit;

Fig. 4 is a side elevation of the cut-off unit or section of the machine showing the same on a larger scale than in Fig. 1;

Fig. 5 is a plan view of such cut-off unit;

Fig. 6 is a transverse sectional view taken through the machine substantially as indicated by line 6—6 of Fig. 3;

Fig. 7 is another transverse sectional view taken through the machine substantially as indicated by line 7—7 of Fig. 4;

Fig. 8 is a partial side elevation of the machine showing the drive for the feed rolls;

Fig. 9 is a partial transverse sectional view taken through the cut-off unit of the machine as indicated by line 9—9 of Fig. 5;

Fig. 10 is a partial end elevation looking toward the cut-off unit as indicated by line 10—10 of Fig. 4;

Fig. 11 is a partial vertical sectional view illus-

trating the mounting for the upper feed rolls, the view being taken as indicated by line 11—11 of Fig. 6;

Fig. 12 is a partial longitudinal sectional view taken through the cut-off unit of the machine as indicated by line 12—12 of Fig. 7;

Fig. 13 is a partial longitudinal sectional view taken on line 13—13 of Fig. 7;

Fig. 14 is another partial longitudinal sectional view taken through the cut-off unit of the machine as indicated by line 14—14 of Fig. 7;

Fig. 15 is a partial transverse sectional view taken through the cut-off unit as indicated by line 15—15 of Fig. 12; and

Fig. 16 is a partial transverse sectional view taken through the cut-off unit of the machine adjacent the main power shaft as indicated by line 16—16 of Fig. 5.

Our novel apparatus for operating on wire stock will now be described in greater detail, and although in so doing, particular reference will be made to the embodiment of the apparatus illustrated in the drawings, it should be understood, however, that the invention is not limited to this particular apparatus but may be embodied in various other similar machines and equipment.

Our improved apparatus comprises in general a wire-drawing unit 20 in which the stock 21 is subjected to an intermittent drawing or sizing operation, a stock feeding and straightening unit 22, and a cut-off unit 23 in which sections or blanks 21a of desired length are cut from the leading end of the stock. Each of the units just referred to will be described in greater detail hereinafter.

The drawing unit 20 corresponds substantially with the wire-drawing machine of United States Patent No. 2,226,400 granted December 24, 1940, and as disclosed in said patent, comprises a frame 24 having a reciprocating slide 25 therein carrying a wire-drawing die 26. The slide 25 may be actuated during the drawing stroke by a lever 27 which is carried by a transverse rock shaft 28. The drawing unit 20 also includes a stock gripping device 29 which grips and holds the stock during the drawing stroke and prevents backward movement of the stock while the die is being pushed thereover. For starting the end of a new section of stock through the machine, the drawing unit may be provided with inching mechanism comprising an inching grip device 30 and an inching feed device 31. As the stock passes into the drawing unit 20, it may be subjected to an initial straightening operation by a reciprocating straightening device 32 which is connected

with the die slide 25 by rods 33. These different elements of the drawing unit to which we have just referred are all described in detail in the above-mentioned United States patent, and further explanation of their construction and operation in the present case is deemed unnecessary.

The feeding and straightening unit 22, which comprises the intermediate section of the machine, is provided with a frame 22a having a pair of feed rolls 34 and 35 at the end thereof adjacent the drawing unit 20 and a second pair of feed rolls 36 and 37 adjacent the cut-off unit 23. Between the two pairs of feed rolls we provide a stock straightening means which acts to straighten the stock immediately after it has been drawn and this device may be any suitable straightener which will accomplish this purpose. In this instance the straightening device comprises banks 38 and 39 of grooved straightening rollers. The individual rollers 38a of the bank 38 lie in a substantially horizontal plane and are arranged in two rows or groups disposed on opposite sides of the stock 21 and with the rollers of one row disposed opposite the intervening spaces of the other row. The bank 39 comprises a similar arrangement of rollers 39a, but the rollers of this bank are arranged to lie in a substantially vertical plane. The banks 38 and 39, as here shown, each comprise seven straightening rollers, although a larger or smaller number of rollers might be employed. The individual rollers of these banks are mounted on blocks 40 which are slidable transversely of the axis of the stock so that the rollers of one row can be adjusted toward or away from the rollers of the other row. The three center rollers of each bank are located or adjusted so that they will produce overbending of the stock in a direction transversely of its axis, as indicated in Figs. 2 and 3. This overbending is shown somewhat exaggerated in Figs. 2 and 3, and in the actual machine is only as much as is necessary to obtain a desired straightness of the drawn stock.

The straightening of the stock at a point in the apparatus immediately following the drawing operation is important and produces improved results not heretofore obtainable. Wire stock such as that on which the present apparatus is designed to operate is supplied to headers, screw machines, or other machines for producing bolts, screws, studs, and a variety of other articles requiring straight cold drawn blanks for their fabrication. This stock is usually cold drawn and is taken up in coils during the drawing operation. These coils are stored until needed and during this time the stock becomes age-hardened. If such age-hardened stock is supplied to a conventional straightening machine, it will be found that the straightened stock will not remain straight, but will acquire a warp corresponding with the bowed or curved contour of the stock while it remained in its coiled condition. Efforts have been made to overcome this tendency by passing the stock through rotary straightening devices, but these have introduced other difficulties such as a tendency to mar the stock and to cause the stock to swell during the cut-off operation. Such rotary straighteners are also subject to rapid wear, because the stock has become age-hardened while in the coiled condition and is difficult to straighten and requires a large amount of overbending.

We have found that by subjecting the stock to a straightening operation immediately following a drawing operation which has been per-

formed in a straight line, the stock is not subjected to uneven strains as caused by coiling and will not thereafter have any tendency to warp or bend when it has been incorporated in blanks or various manufactured articles. The stock is drawn in a straight line by the reciprocating action of the drawing die 26 and is then subjected to a straightening operation while it is still free from age-hardening. When cold drawn coiled stock is supplied directly to the action of a straightener, the stock can twist and skew as it advances and this causes uneven strains in the stock which also produce warping and interfere with the accuracy of the cut-off operation. The gripping device 29 holds the stock from twisting or skewing during the drawing stroke and the drawing die holds the stock against twisting or skewing during the feeding of the stock, and therefore such uneven strains will not occur in the stock. The straightening operation, as above explained, consists in subjecting the stock to overbending in two different transverse planes, but which need be only a relatively slight amount of overbending. The important thing is that the stock is drawn in a straight line, is held against twisting or skewing, and is straightened immediately following the drawing operation, and we have found that with stock which has been thus treated, the blanks can be cut off more accurately as to length and the articles manufactured therefrom will remain straight indefinitely.

We find it desirable to employ the two pairs of feed rolls above referred to because this permits one pair of feed rolls 34 and 35 to be located immediately adjacent the drawing unit 20 to receive the drawn stock therefrom and feed the same through the banks 38 and 39 of straightening rollers. The other pair of feed rolls 36 and 37 can be located between the straightening means and the cut-off mechanism, and when a coil of stock is used up and the end passes through the feed rolls 34 and 35, the other pair of feed rolls 36 and 37 will continue to feed the stock into the cut-off unit 23.

As shown in the drawings, the feed rolls of each pair have peripheral grooves which grip the stock and advance the same as the rolls are driven intermittently. The lower rolls 34 and 36 are actuated by driving the shafts 34a and 36a upon which they are mounted and the upper rolls are mounted on shafts 35a and 37a which are driven from the shafts of the lower rolls by the spur gears 41 and 42. The shafts 34a and 36a are journaled in the frame 22a to rotate on fixed axes and are driven in a manner to be presently explained.

A novel mounting arrangement for the upper rolls 35 and 37 permits these rolls to swing toward or away from the lower rolls to properly grip the stock. Since the mountings for both of the upper rolls are substantially identical, it is only necessary to describe the mounting arrangement for the roll 35. The shaft 35a carrying the upper roll 35 is journaled in a swinging head 43 which has a hinge connection 44 with the frame 22a at a point offset laterally from the plane of the rolls. The frame 22a has an upwardly extending forked portion 46 thereon providing a recess or guideway 47 in which the swinging head 43 is vertically movable. A compression spring 48 located in a recess of the frame 22a at a point beneath the head 43 acts on the latter in a direction tending to separate the upper roll 35 from the lower roll 34. The roll 35

may be shifted or yieldably pressed toward the roll 34 for the desired extent by means of a compound lever arrangement adapted to act on a rounded projection 59 of the head 43. This compound lever arrangement may comprise a lever 51 having a hinge connection 52 at one end thereof with the frame 22a and a second lever 53 yieldably fulcrumed on the frame and having a cam or eccentric portion 54 engageable with the outer end of the lever 51. The fulcrum for the lever 53 may comprise a forked member or yoke 55 having a threaded stem 56 extending through the opening of a lug 57 of the frame. A compression spring 58 surrounding the stem below the lug 57 acts on the yoke 55 to cause the compound lever to yieldably shift the feed roll 35 toward the roll 34. With the arrangement just described, it will be seen that the lever 53 will be very easy to operate because its force is applied to the lever 51 through the eccentric portion 54, and it is only necessary to swing the lever 53 about its pivot 53a to cause closing or opening of the feed rolls. A pair of lock nuts 58a may be provided on the stem 56 as an adjustable abutment which determines the extent to which the yoke 55 can be moved by the spring 58. The springs 49 and 58 are so selected that when the lever 53 is swung upwardly to release the spring 58, the spring 49 will lift the head 43 to separate the rolls and when the lever 53 is swung down to the position shown in the drawings, the action of the levers and the spring 58 will shift the head 43 downwardly, compressing the spring 49 and pressing the roll 35 against the stock 21.

In the present apparatus, the pairs of feed rolls are driven intermittently and for the proper interval to advance the stock after each drawing stroke of the die slide 25. To obtain this timed actuation of the feed rolls we find it desirable to drive the rolls from the actuating means for the die slide. As mentioned above, the die slide is actuated by the swinging lever 27 which is carried by the transverse rock shaft 28. The lever 27 may be actuated by a link or connecting rod 60 which connects the lower end of this lever with a transverse shaft 61 journaled in the frame 22a. The link 60 may be connected with the shaft 61 by means of an eccentric block 62 which is adjustable relative to the axis of the shaft for varying the drawing stroke of the die slide 25. The rock shaft 28 also carries a lever 63 which is connected with the shaft 34a of the lower feed roll 34 by means of a link 64 and a clutch 65 having an arm or lever 65a with which the link is connected.

The clutch 65 is a one-way clutch of a construction known to those skilled in the art and is arranged so that the clutch arm 65a will have an idle stroke during the drawing stroke of the die slide 25, and will have a working stroke during the return stroke of the lever 27. When the clutch arm 65a swings through its idle stroke the feed rolls remain stationary, the stock at this time being held against backward movement by the gripping device 29 while the drawing die is being pushed over the stock by the working stroke of the die slide 25. During the working stroke of the clutch arm 65a, the clutch 65 drives the shaft 34a and the feed roll 34 mounted thereon. This same movement of the shaft 34a drives the upper feed roll 35 through the gears 41 and 42. The movement thus imparted to the feed rolls 34 and 35 feeds the stock forward while the slide-actuating arm 27 travels through its return stroke and

the forward movement of the stock pulls the die slide 25 up against the lever 27 so that the die slide will be ready for the next drawing stroke.

The second pair of feed rolls 36 and 37 may be driven from the shaft 34a of the feed roll 34 by means of a chain 66 extending around the sprockets 67 and 68. The sprocket 67 is carried by the shaft 34a and the sprocket 68 is carried by the shaft 36a of the feed roll 36. The stroke or driving interval of the two sets of feed rolls can be adjusted or varied with respect to the stroke of the die slide 25 by adjusting the position of the block 69 in the forked portion of the lever 63.

The cut-off unit 23 of the machine comprises a frame 23a having thereon an elongated hollow member or stock guide 70 into which the stock is fed from the feed rolls 36 and 37, and a pair of shearing dies 71 and 72 located between such hollow member and the feed rolls and adapted to shear the stock after the desired length has been fed into the hollow member. The hollow member 70 may comprise a bar suitably mounted on the frame 23a and having a longitudinally extending groove or recess 70a therein. The bar is preferably arranged with the groove or recess on the bottom or underside thereof, as shown in Figs. 7 and 9, so that when the section of stock has been cut off by the dies 71 and 72, it can drop from the member 70 onto an inclined section 73 of the frame, from which it slides or rolls into the trough 74.

For supporting the stock while it is being fed into the hollow member 70, we provide a shutter 75 which forms a closure for the groove 70a. This shutter may be in the form of an angle bar, as shown in the drawings, and is carried by a plurality of longitudinally spaced swinging arms 76 so that the shutter may be moved away from the groove of the member 70 to release the section of stock therefrom. The arms 76 may be connected with a rock shaft 77 to which rocking movement is imparted for opening the shutter in timed relation to the cutting of the stock, as will be presently explained.

The die 71 is a stationary hollow die which is suitably mounted in the frame 23a and through which the stock is fed into the hollow member 70. The die 72 is in the form of a cutter or blade movable transversely of the hollow die 71, and may be carried by a slide 78 which is reciprocable in a guideway provided in the frame. The slide 78 has an opening 78a through which the stock extends below the cutter 72, so that upon downward movement of the slide, the stock will be cut with a shearing action. The cutter 72 may be connected with the slide 78 by means of the adjusting and clamping screws 79 and 80.

For actuation of the cut-off slide 78 and the other mechanism associated therewith, we provide a driven shaft 81 extending transversely of the cut-off unit 23 and suitably journaled in the frame 23a thereof. The cut-off slide 78 may be actuated from the shaft 81 by means of a link or connecting rod 82 and an eccentric 83 mounted on the shaft and engaged by the link. The shaft 81 may have a fly wheel 84 thereon which is driven from a suitable power device such as the electric motor 85 by means of a suitable belt 86 or the like. The fly wheel 84 is not keyed to the shaft 81, but is keyed to a sleeve 87 which is journaled on the shaft and cooperates with a clutch 88. The fly wheel may rotate continuously, but the shaft 81 is driven only when a section of stock is to be cut off. The clutch 88 is of the

kind known as a single-revolution clutch, and since clutches of this kind are well known in the art, it need not be described in detail. When this clutch is engaged, in a manner to be presently explained, it connects the fly wheel 84 with the shaft 81 and causes the shaft to be driven for a single revolution, whereupon it automatically disconnects the fly wheel from the shaft. During this single revolution of the shaft 81, the cutter 72 makes one stroke and cooperates with the die 71 to shear the stock.

The mechanism for controlling the cut-off operation will be described next. This mechanism includes a stock gauge 89 having an arm portion or finger 89a located in the hollow member 70 and adjustable therewith for varying the length of sections to be cut from the stock. The stock gauge 89 also has a block or head portion 89b slideable in an elongated hollow gauge guide 70b and the gauge can be adjusted longitudinally of the hollow member 70 by means of a rotatable screw 90 extending through a threaded opening in such block or head portion. The screw 90 may be rotated by means of the pinion 91 and driving gear 92 located at the outer end of the frame 23a. The pinion 91 is connected with the screw 90 and rotates the latter in one direction or the other when the gear 92 is driven by the handle 93. This can be done while the machine is in operation and is a distinct advantage for making fine adjustments for length of blanks without stopping the machine.

The stock gauge 89 also has limited movement in the hollow member 70 in response to the engagement of the stock with the gauge, and this limited movement is utilized to trip the clutch 88 by which the fly wheel 84 is connected with the shaft 81. The inner end of the gauge screw 90 carries a pair of spaced collars or abutments 94 and 95 which are pinned or otherwise connected to the gauge screw. A forked lever 96 engages the collar 94 and is mounted on a transverse shaft 97 so that outward movement of the gauge screw will cause rocking of this transverse shaft. The shaft 97 carries a latch lever or trigger 98 which cooperates with an arm 99a of a star lever 99.

The star lever 99 may also be referred to as the clutch control lever and is journaled to rock on a transverse shaft 100. An arm 99b of the star lever carries a roller 101 which, as will be presently explained, cooperates with a cam 102 mounted on the shaft 81. An arm 99c of this same lever cooperates with the clutch 88 and is normally in engagement with the shoulder or abutment 103 thereof, as shown in Fig. 12. A fourth arm 99d of the star lever 99 is connected with a rod 104 which extends through a lug 105 and is acted upon by a compression spring 106 surrounding the rod between the lug and an abutment 107 provided adjacent the outer end of the rod. The spring 106 exerts a pull on the arm 99d tending to swing the star lever 99 in a direction to disengage the arm 99c from the clutch abutment 103 but the latch lever 98 normally engages the arm 99a and prevents such swinging of the star lever.

When the stock is fed into the hollow member 70 and engages the stock gauge 89, it moves the gauge outwardly for the limited amount above mentioned, thereby pulling the gauge screw 90 in a corresponding direction and rocking the shaft 97 by means of the lever 96. The rocking of the shaft 97 swings the latch lever 98 upwardly, thus releasing the arm 99a and permitting the spring 106 to swing the star lever in a

clockwise direction, as seen in Fig. 12, thereby disengaging the arm 99c from the clutch abutment 103, and at the same time swinging the arm 99b in a direction to press the roller 101 against the surface of the cam 102. At the time that the latch lever 98 is tripped in the manner just explained, the cutter slide 78 is in its upper position and the cam 102 then stands with its low point 102a opposite the roller 101. When the arm 99c is disengaged from the abutment 103 of the clutch 88, the clutch is thereby tripped and connects the fly wheel 84 with the shaft 81. The shaft 81 now makes one revolution, thereby actuating the cutter slide 78 and cutting off the section of stock which has been fed into the hollow member 70. During this revolution of the shaft 81, the roller 101 rides on the cam 102, and by the time that the one revolution of the shaft has been completed, the high point 102b of the cam will have arrived under the roller 101 and will have rocked the star lever 99 in a counter-clockwise direction, as seen in Fig. 12, to reengage the arm 99c with the clutch abutment 103, which disengages the clutch thus disconnecting the fly wheel from the shaft. This counter-clockwise movement of the lever 99 sweeps the arm 99a across the beveled face 98a of the latch lever 98, whereupon the arm 99a is caught and held by the shoulder or trigger portion 99b of the lever 98. The latch lever 98 is normally swung toward engagement with the arm 99a by the action of a compression spring 108 on a lever 109 connected with the shaft 81.

To lessen the shock resulting from the engagement of the clutch abutment 103 with the arm 99c of the lever 99, we may provide the arm 99c with a movable thrust block 110 which is cushioned by a compression spring 111 suitably mounted in a recess of the arm. In addition to this cushioning means on the arm 99c, we may decrease the momentum of the clutch 88 by slowing down the shaft 81 during or just prior to the engagement of the clutch abutment 103 with the thrust block 110. For this purpose we may provide a suitable friction brake 112 arranged to act on the shaft 81 as shown in the drawings. This brake also acts to stop the shaft 81 after the clutch is disengaged.

It will be seen from the foregoing explanation that when the cutter 72 starts its downward movement to shear the stock, the outer end of the stock is being held against the stock gauge 89 by the feed rolls so that the length to be cut will be accurately gauged. As soon as the cutter bites into the stock it will be held by the cutter and the gauge can then be moved away from the stock so that the severed section or blank can drop freely out of the hollow member 70 as soon as the shearing operation is completed. For thus moving the gauge we provide a pair of levers 113 and 114 which are mounted on and keyed to the transverse shaft 100 at laterally spaced points and a cam 123 with which the lever 114 cooperates.

The lever 113 has an opening in the head thereof through which the gauge screw 90 extends. This opening of the lever 113 has a counter-bore 113a in which is located a compression spring 116. The collars 94 and 95 of the gauge screw 90 are spaced apart a greater distance than the thickness of the head of the lever 113 so that there will be some lost motion between the lever and the collar 95. The spring 116 normally pulls the gauge screw inwardly and holds the collar 94 against the lever 113, but during

the initial outward movement of the gauge screw resulting from the engagement of the stock with the gauge 89, the spring 116 will yield and permit the lost motion between the collar 85 and the lever 113 to be taken up. This predetermined limited outward movement of the gauge screw thus permitted by the spring 116 is sufficient to actuate the latch lever 98 to release the arm 99a of the star lever 99.

The lever 114 is a bell crank lever of which the downwardly extending arm 114a carries a roller 117. The arm 114b is connected with a rod 118 carrying an abutment or spring seat 119 against which the compression spring 120 acts. The opposite end of the compression spring engages a seat 121 which can be adjusted inwardly or outwardly by the screw 122 to vary the compression of the spring. The roller 117 cooperates with the cam 123 which is mounted on the shaft 81, and the spring 120 normally holds the roller 117 against the cam. During the single revolution of the shaft 81, which produces the cutting stroke of the slide 78, the roller 117 descends the cam 123 and the spring 120 thereupon rocks the levers 114 and 113 causing the gauge screw 90 to move the gauge 89 away from the end of the stock 21. After the stock has been severed by the cutter 72, the roller 117 ascends the cam 123, thereby swinging the levers 114 and 113 in the opposite direction and causing the gauge screw 90 to pull the gauge 89 back to its regular position ready to be again engaged by the leading end of the stock when the latter is fed into the hollow member 70.

It was stated above that the shutter 75 is swung to an open position during the cut-off operation to permit the severed section of stock to drop out of the hollow member 70. For actuating the rock shaft 77 to thus swing the shutter 75 we provide a cam 124 on the shaft 81 and a lever 125 which is actuated by this cam. The lever 125 may be pivoted on the shaft 100 and the arm 125a thereof may carry a roller 126 which engages the cam 124. The other arm 125b of this lever is connected with the rock shaft 77 by the links 127 and 128, the bell crank lever 129, and the lever arm 130. When the shaft 81 is rotated during the cutting operation, the lever 125 will be rocked by the cam 124 and will cause the shutter to be swung to its open position shown in broken lines in Fig. 9. After the cutting operation is completed, the roller 126 descends the cam 124, and the lever 125 is swung in a direction to close the shutter 75 by the action of the spring 131.

We have explained above that the cut-off slide 78 and the associated mechanism are actuated from the shaft 81, which is driven by the electric motor 85, and have also explained that the die slide 25 and the two pairs of feed rolls are actuated from the shaft 61. It should also be explained that the shaft 61 may be driven from the shaft 81 as by means of a chain 132 extending around the sprockets 133 and 134. By driving the shaft 61 from the shaft 81, it will be seen that the drawing, feeding, and cut-off operations can all be carried out in timed sequence to each other. In connection with the cut-off operation, it should likewise be explained that when the leading end of the stock 21 is fed against the stock gauge 89 and shifts the latter through the limited distance which releases the latch lever 98, the stock remains in engagement with the gauge 89 until the die 72 actually begins to cut into the stock. There is, therefore,

an interval of time when the forward movement of the stock ceases while the two pairs of feed rolls are still being driven. When this occurs, the feed rolls slide relative to the stock, but inasmuch as this is only for a relatively short interval, no damage is done to the stock.

When a new length of stock is started through the machine, it may be desirable to cut one or more sections off of the leading end for purposes of adjusting or testing the apparatus and also to get rid of any irregular portion which may occur at the leading end of the stock. To enable the operator to initiate such a cut-off operation whenever desired, we provide a manually operable trip lever 135 which is connected with the rock shaft 97. When this trip lever is swung to the left, as seen in Fig. 12, it will lift the latch lever 98 to release the star lever 99 and initiate a cut-off operation in the same manner as if the latch lever 98 had been lifted as the result of the engagement of the leading end of the stock with the gauge 89.

From the foregoing description and the accompanying drawings, it will now be understood that we have provided novel apparatus for operating on wire stock and with which blanks cut accurately to a desired length can be produced rapidly and economically and such blanks will be entirely free of the tendency to warp or buckle.

While we have illustrated and described our novel apparatus in a more or less detailed manner, it will be understood, of course, that we do not wish to be limited to the particular procedure and apparatus herein described in detail, but regard our invention as including such changes and modifications as do not constitute a departure from the spirit of the invention and the scope of the appended claims.

Having thus described our invention, we claim:

1. In apparatus of the character described, a pair of cooperating feed rolls adapted to receive therebetween a strand of wire stock to be fed, a frame member having one of said rolls mounted thereon and having a guideway therein above said one roll, a head carrying said second roll, said head being hinged to said frame member for movement in said guideway, a lever pivoted on said frame at one side of said guideway and engageable with said head, a fulcrum at the other side of said guideway and movably connected with the frame by means including a compression spring, and a second lever pivoted on said fulcrum and having a cam portion held against the first lever by the action of said spring on said fulcrum.

2. In apparatus of the character described, a pair of cooperating feed rolls adapted to receive therebetween a strand of wire stock to be fed, a frame member having one of said rolls mounted thereon and having a guideway therein above said one roll, a head carrying the second roll and movable in said guideway, a spring acting on said head in a direction to separate said rolls, a lever acting on said head to close the rolls, said lever being pivoted on said frame at one side of said guideway, a fulcrum at the other side of said guideway and movably connected with the frame by means including a compression spring, and a second lever pivoted on said fulcrum and having a cam portion held against the first lever by the action of said spring on said fulcrum.

3. In apparatus of the character described, a

pair of cooperating feed rolls adapted to receive therebetween a strand of wire stock to be fed, a frame member having one of said rolls mounted thereon and having a guideway therein above said one roll, a head carrying the second roll and movable in said guideway, a spring acting on said head in a direction to separate said rolls, a lever arranged to act on said head to close the rolls, a yoke adjacent the outer end of the first lever and having yieldable connection with said frame member, and a second lever fulcrumed on said yoke and having an eccentric portion engaging the first lever adjacent its outer end.

4. In apparatus of the character described, a stock gauge, a pair of feed rolls engageable with wire stock for feeding the same against said gauge, a cutter spaced from the gauge, means for actuating the cutter including a movable control member, said gauge being capable of predetermined movement in response to the engagement of the stock therewith and being connected with said control member so that said predetermined movement causes actuation of the latter, said feed rolls being capable of relative sliding on the stock for holding the same against the gauge so that the stock length will be accurately gauged for the cut-off operation, and means for moving the gauge away from the stock during the cutting operation.

5. In apparatus of the character described, a stock gauge, means for feeding wire stock longitudinally against said gauge, a cutter spaced from said gauge and operable to sever a corresponding length from said stock, said stock gauge being capable of predetermined movement in response to the engagement of the stock therewith, means controlled by such movement of the stock gauge and operable to cause actuation of said cutter, and means for moving the gauge away from the stock substantially upon engagement of the cutter with the stock.

6. A cut-off apparatus for wire stock comprising, a cutter adapted to sever the stock, an elongated hollow member having a bottom opening and a movable shutter closing said bottom opening, a stock gauge spaced from the cutter to correspond substantially with the length of stock desired, means for feeding the stock into said hollow member and against said gauge, means for actuating said cutter, said stock gauge being movable in response to engagement of the stock therewith, a movable control for the cutter actuating means adapted to be actuated by such movement of the stock gauge, means for moving the gauge away from the stock during the cutting operation, and means for opening said shutter in timed relation to the actuation of said cutter.

7. A cut-off apparatus for wire stock comprising, a cutter adapted to sever the stock, an elongated hollow member having a bottom opening and a movable shutter closing said bottom opening, a stock gauge in said hollow member, means for feeding the stock into said hollow member

and against said gauge, means for actuating said cutter, said stock gauge being adjustable along said hollow member to vary the length of stock to be cut and having limited movement in response to engagement of the stock therewith, means for adjusting the position of the stock gauge, means for actuating said cutter, a movable control for the cutter actuating means adapted to be actuated by said limited movement of the stock gauge, means for moving the gauge away from the stock during the cutting operation, and means for opening said shutter in timed relation to the actuation of said cutter.

8. A cut-off apparatus for wire stock comprising, a cutter adapted to sever the stock, an elongated hollow member, means for actuating said cutter, a trip device controlling the cutter actuating means, a rod extending longitudinally of said hollow member and connected with said trip device, a stock gauge in said hollow member and connected with said rod, said gauge and rod being capable of predetermined movement to actuate said trip device in response to engagement of the stock with the gauge, means for moving the gauge away from the stock during the cutting operation, and means for feeding the stock into said hollow member and against said gauge.

9. A cut-off apparatus for wire stock comprising, a cutter adapted to sever the stock, an elongated hollow member, means for actuating said cutter, a trip device controlling the cutter actuating means, a rod extending longitudinally of said hollow member and connected with said trip device, a stock gauge in said hollow member and connected with said rod, said gauge and rod being capable of predetermined movement to actuate said trip device in response to engagement of the stock with the gauge, means for feeding the stock into said hollow member and against said gauge.

10. In apparatus of the character described, a stock gauge, means for feeding wire stock against said gauge, a cutter spaced from the gauge and operable to sever the stock, means for moving the gauge in the direction of stock travel for shifting the gauge away from the stock during the cutting operation, and a common shaft for actuating said cutter and said gauge moving means.

11. In apparatus of the character described, an elongated hollow member having a stock discharge opening, a stock gauge in said hollow member, means for feeding wire stock into said hollow member and against said gauge, a cutter spaced from said gauge and operable to sever the stock, a shutter closing said stock discharge opening and being movable to release the severed stock, means for moving said gauge away from the stock during the cutting operation, and a common shaft for actuating said cutter, said movable shutter and said gauge moving means.
